UNITED STATES PATENT OFFICE

2,098,272

THERAPEUTIC APPARATUS

Simon Benson, Chicago, Ill.

Application March 25, 1935, Serial No. 12,863

19 Claims. (Cl. 128—38)

My invention relates to therapeutic apparatus.

More particularly it relates to apparatus for subjecting a member or area of a patient's body to abatmospheric (that is, either above or below atmospheric) treatment and to an apparatus and method for effecting an air-tight seal between the member or area undergoing treatment, and the chamber or receptacle whereby the treatment is administered. This abatmospheric treatment or fluid pressure treatment (the fluid usually being air) may be by either negative pressure or positive pressure, or it may be by both alternately.

The most usual purpose of this type of abatmospheric pressure treatment is for obliterative vascular diseases and its contemplated function is to stimulate circulation through existing vascular systems including the peripheral systems and also to establish detour vascular systems about the obliterations.

The chief object of my invention is the provision of a seal which is non-constrictive of the vascular circulation. Seals now commonly in use are of a type which tend to press against the tissues of the member or area and thereby constrict circulation, and especially the outer or venous circulation, thereby defeating the very purpose of the treatment. This constriction has made it necessary to interrupt negative pressure treatment at intervals by allowing the treatment chamber pressure to come up to atmospheric pressure or to build up to a positive pressure so venous blood, retarded by the constriction of the seal, may be cleared and the patient be given some momentary relief from the often acute pain resulting from the stifling of the venous circulation by the constriction of the seal and this periodic interruption of the suction to build up atmospheric or positive pressure in the treatment chamber has been necessary even in those instances where, from the standpoint of the treatment itself, it would be preferable to maintain an uninterrupted suction for a long period of time.

In general, I realize my object by bringing the skin of the member or area away from the body and against the sealing ring in sealing contact therewith, as distinguished from bringing the sealing ring down against the skin and into pressure against the subcutaneous tissues. Preferably I accomplish this by pneumatically sucking the skin outwardly against a sealing ring and into sealing contact therewith. My seal is such that it may be used, even without alteration or adjustment, for either negative or positive pressure in the treatment chamber or for treatment where the chamber is subjected to negative and

positive pressure alternately or where the pressure alternates between negative or positive and atmospheric pressure.

Another and auxiliary object of my invention is the provision of such a non-constrictive seal in the two somewhat different instances of a limb, where an encircling sealing ring may be used, and a more or less flat body area where the seal will not come along a radial face of the sealing ring, but at the lateral face thereof. The gist of the distinctions between these two instances is that with a limb, where an encircling seal may be used, the suction in the treatment chamber is more or less balanced radially of the limb, whereas in the instance of the flatwise application of the sealing ring, suction within the treatment chamber tends to pull the chamber itself against the body, thereby creating an inward pressure which still further aggravates the objectionable vascular constriction.

Another object of my invention is concerned with pressure control means whereby the treatment chamber is subjected to negative and positive pressure alternately.

The foregoing, together with further objects, features and advantages of my invention are set forth in the following description of specific embodiments thereof and illustrated in the accompanying drawings, wherein:

Fig. 1 is a diagrammatic view in elevation of apparatus for subjecting an arm to fluid pressure in a chamber;

Fig. 2 is a plan view of the chamber and sealing cuff;

Fig. 3 is a vertical sectional view of the cuff and cover of the chamber, taken along the line 3—3 of Fig. 2;

Fig. 4 is a detail view of the cuff, taken along the line 4—4 of Fig. 2;

Fig. 5 is a longitudinal vertical section of a treatment chamber of the type adapted to receive a leg, and incorporating another and preferred form of seal;

Fig. 6 is an enlarged vertical section through the sealing ring of Fig. 5;

Fig. 7 shows in radial section a modified form of sealing ring;

Fig. 8 shows in radial section still another form of sealing ring;

Fig. 9 is a transverse detail section of the seal of the form of Fig. 8, taken on the line 9—9 of Fig. 8;

Fig. 10 shows still another modified form of seal in radial section;

Fig. 11 shows in vertical section a treatment

chamber and sealing ring of the type adapted for application more or less flatwise to a body area;

Fig. 12 is a side elevation of the pressure generating and controlling apparatus, showing in connection therewith the chamber of Fig. 5;

Fig. 13 is a vertical transverse section of the pulley wheels, taken on the line 13—13 of Fig. 12;

Fig. 14 is a radial section, taken on the line 10 14—14 of Fig. 12 through the rim of the cam wheel, showing a typical cam block;

Fig. 15 is a perspective view of a typical cam block for the cam wheel;

Fig. 16 is a development of the built-up cammed 15 periphery of the cam wheel, and

Fig. 17 is a horizontal section of the regulating valves, taken on the line 17—17 of Fig. 12.

This application constitutes a continuation in part of my application Serial No. 515,350, filed 20 February 12, 1931, on Apparatus for sealing.

In the form of Figs. 1 to 4, inclusive, I have shown a vertically disposed cylindrical chamber 21 large enough to contain comfortably a man's arm. An air-tight cover 22 is secured to the top 25 of the chamber in any readily removable fashion. The cover has an inlet 23 and an outlet 23a, each provided with a stop cock. The cover has a central opening conforming to the shape of the portion of the body member to be sealed. A sealing 30 ring or cuff 24 is fitted into this opening and securely attached to the cover. The cuff may be made of metal, glass, hard rubber, or composition materials. As shown in Fig. 4, the vertical surface of the cuff is slightly concave and the 35 horizontal section follows the cross-section of the body member to be sealed.

It is essential that the portion of the member upon which the seal is to be made when the member is in the chamber be in close proximity to 40 the inside wall of the cuff, but it must not fit so snugly that the circulation of the blood is in any manner constrained or impaired. Since the size and shape of men's, women's and children's limbs vary greatly, and since on some occasions 45 it will be desirable to seal the entire leg or arm of the patient, and on others just a portion of the member, it is necessary for doctors and others giving treatments, as hereinafter described, to have available a supply of cuffs of different sizes 50 and shapes. However, cuffs fashioned from hard rubber or a composition material and provided with slots to receive sections to enlarge the cuff have eliminated somewhat the necessity of maintaining a supply of cuffs of different sizes.

55 The cuff preferably consists of an inner and outer casing forming a double wall for the cuff or sealing ring, with an annular recess or chamber 25 between the casings or walls. The outer casing 26 is rigid and rests upon and is secured 60 to the top of the cover. The elliptical inner wall or casing is comprised of three parts, as best shown in Fig. 4, the top section 27 being a continuation of the outer casing 26 bent over in the nature of a bead, thus forming a closure for 65 the recess 25 between the walls. The lower section 28 of the inner wall is fitted into the opening of the cover and is secured to the inner side of the cover and extends somewhat above it. A section of foraminous material 29—preferably 70 fine mesh wire screening—extends between and inwardly of the upper and lower sections, completing the inner wall of the cuff. As previously stated, the three sections of the inner wall are carefully shaped to follow the contour of the 75 sealed body member. The various parts may be

of metal secured together in a leak-proof manner, for example by soldering.

As shown diagrammatically in Fig. 1, the tubing 30 connects the air recess 25 of the cuff with a vacuum pump 31 and a manometer 32. The 5 vacuum pump 31 is employed to reduce the pressure in the air recess 25. The chamber 21 is here shown as containing water as the fluid medium. A seal is effected between the chamber and the arm by sucking the skin of the arm adjacent the cuff 24 against the concave inner wall of the cuff. This sucking is accomplished by reducing the pressure in the air recess 25 by operating the vacuum pump 31. The skin adjacent the entire inner wall is thus drawn tightly 10 against said wall and forms an effective seal. In case the skin should be drawn away from the cuff in any manner, the break in the seal would be immediately reflected in the manometer 32. The advantage of my apparatus lies in the fact 15 that an air-tight seal is secured without in any way constricting the flow of blood in the enclosed member.

I shall next describe the apparatus for subjecting the chamber 21 to negative or positive 20 pressure. Tubing 34 connects a graduate 33 with the chamber past a stop cock 35. Another manometer 36 and another pump 37 (capable of producing both negative and positive pressure) are separately connected to the graduate 33. In 25 operation, the patient's forearm—or, in apparatus of different size and shape, the patient's leg—is placed within the chamber 21 and the cuff 24. The arm and cuff are then sealed in the manner described and the chamber and tubing to the 30 inlet to the graduate filled with water (if a liquid medium is to be employed) through the inlet 23, the stop cock 35 being open while the chamber and tubing are being filled.

When the apparatus is used for therapeutic 40 treatment, the pump 37 is operated to intermittently reduce and increase the pressure within the chamber. This may be done, for example, by reversing the motor of the pump, or by connecting the conduit to the chamber alternately to the 45 negative and pressure sides of the pump, depending of course upon the type of pump employed.

In Figs. 5 and 6, I have shown another and preferred form of sealing apparatus in conjunction 50 with another form of chamber, this chamber being shown as adapted for the reception of a leg. Here the chamber 41, which is glass-walled for ready observation of the leg, is of generally cylindrical shape except that it has an upper enlargement 41' for the accommodation of the toes and fittings. A pressure inlet fitting 42, which preferably includes a pressure gage, is inserted into the chamber at the top of the enlargement 41' by means of a rubber stopper, for example, and is 55 connected with the chamber end of a treatment pressure hose 43 leading from a regulated source of pressure, which as hereinafter explained may be either negative pressure or positive pressure, or both alternately. The chamber is preferably 60 provided also with a thermometer 44 and an electric heating unit 45, it being desirable in many instances to conduct a treatment under controlled 65 elevated temperatures.

The open end of the glass chamber 41 through 70 which the leg is inserted, is provided with a sealing cuff 46 of rubber or other flexible but not limp material. The cuff may be of frusto-conical shape with its enlarged end embracing the beaded end of the chamber 41 and secured thereto by a

clamping ring 41. The smaller or outer end of the cuff 46 forms a sealing ring 48. To prevent collapsing of the cuff under internal suction, while permitting considerable flexibility, I prefer 5 to incorporate longitudinal stays 49 at radially spaced intervals, which stays may be molded into the rubber of the cuff. The sealing ring 48 may be of rubber molded integrally with the body of the cuff. The rubber of the ring 48 is preferably 10 of about the flexibility of the tread of an automobile tire or slightly more resilient and flexible. To be precise, the ring should be resilient enough easily to adapt itself to varying oval shapes, out of its normal round, so that it will adapt itself 15 to the contour of a patient's legs, and still not be so limp that it will buckle and thereby en- small its circumference, for the latter would result in a constriction of the limb.

The ring 48 has an inner skin-engaging face 20 50 which opens into a sealing recess or chamber 51 by a slot 52 through the sealing face, leaving annular corners 53. A nipple 54 molded into the outer wall of the sealing ring 48 receives the end of a sealing suction hose 55 from a suction source 25 which will later be described. The cuff 46 is chosen from an available assortment of sizes so that the inside diameter of the sealing ring 48 is approximately that of the region of the leg to be treated at some convenient point above the 30 knee. Advantage can be taken of the normal taper of the thigh to avoid the necessity of exact size for the sealing ring, the leg being pushed in until the tapering thigh substantially fits the sealing ring which, as previously mentioned, is 35 easily deformed to accommodate itself to the oval cross-section of the thigh. When the recess 51 is subjected to the sealing suction through the hose 55, the skin is drawn into the recess, making sealing contact all around the thigh at two longitudinal 40 spaced circles defined by the salient corners 53 over which the skin is thus drawn. But to avoid drawing the skin so far into the recess 51 that the skin will become unduly stretched over the corners 53 and become painful, I provide 45 a skin-supporting foraminous wall 56 of woven wire or perforated sheet stock, molded into the rubber of the sealing ring 48, as shown in Fig. 6. This limits the in-drawing of the skin, but little step-down being required to render the salient 50 corners 53 effective for sealing contact.

As far as the sealing itself is concerned, this may be accomplished by the modification shown in Fig. 7, where the sealing ring 48a has a narrow slot 52a in its skin-engaging face 50a leading to 55 the suction recess 51a, but no supporting wall is used across the recess. The skin will be sucked into effective seal with the closely spaced salient corners 53a, but, as compared with the form of Fig. 6, this has two objections. One is that the 60 skin will be drawn out into the slot to form a narrow but high ridge, which will prove painful to the patient and leave an objectionable ring for some time. The other objection is that the total area of the skin subjected to the sealing suction 65 is much less and, therefore, the skin can be torn away from sealing contact with the sealing ring by lesser force than is required in Fig. 6, for example, where the area of skin subjected to suction is considerably greater.

In Figs. 8 and 9, I have shown a further modification of sealing ring 48b where the skin-engaging faces 50b may be formed by a pair of metal rings each of L-shaped radial section, although the same principle may be worked out all in 70 molded rubber. Here the slot 52b defining the

salient corners 53b does not open directly into the sealing recess 51b, nor is there a perforated skin-supporting wall. Instead, the skin-supporting wall 56b is imperforate, but spaced from the back side of the skin-engaging face 50b by fluted edges 54b'. Thus, the sealing suction to which the recess 51b is subjected finds its way to the skin around the lateral edges of the wall 56b and sideways into the slot 52b.

In Fig. 10 I have shown a still further modification of the sealing ring. Here the sealing ring 48c is built up from thin and rather flexible sheet metal and the skin-engaging face 50c is flush with a central perforated area 54c without employing outstanding annular corners such as 53. This 10 form of seal is not so satisfactory in operation because, lacking the annular sealing ridge 53, a 15 pull on the skin away from the sealing face 50c can easily overcome the small force of the suction on the area of one or two of the holes of the 20 perforated area, freeing them independently of the others. Then, another two or three can be released independently of the others, and so on, until the entire seal is broken by increments. Also, as the skin is drawn away from more and 25 more holes, the atmospheric leakage into the sealing recess 51c reduces the suction therein and further contributes to the ready collapse of the 30 entire seal.

When the treatment chamber 41 is subjected to 35 negative pressure, it will tend to suck the leg in farther into the treatment chamber by a force representing the pressure times the area encompassed by the sealing ring 48. Pulling the leg 40 farther into the treatment chamber would have the objections of longitudinally stretching the skin of the contained leg (inasmuch as the seal 48 will not permit the slipping of the skin) and of the tapered thigh when moved farther in, bringing a region of the thigh of larger diameter into 45 the sealing ring to the extent allowed by the sliding of the skin upon the subcutaneous tissues, thereby constricting circulation. To prevent such inward movement of the leg I provide a foot- 50 rest R within the treatment chamber which foot-rest may be adjusted by external manipulation of a screw which is threaded through a bushing in the end wall of a chamber, as shown in Fig. 5. Or, the treatment chamber and the body may each be secured to the bed or treatment table.

When the treatment chamber is subjected to 55 positive pressure, there is a corresponding tendency to push the leg out. This may be remedied by the latter suggested arrangement or by suitably harnessing the treatment chamber to a waist belt or shoulder yoke.

In Fig. 11 I have shown a modified arrangement of seal adapted to a treatment chamber which is applied more or less flatwise against a body area in those instances where the part to be 60 treated is not in the nature of a limb which can be encircled by the sealing ring. In other words, Fig. 11 shows an arrangement where the sealing ring faces the body sidewise with its lateral face against the body, as distinguished from the forms 65 previously described, where the seal may be effected radially by contact with the inner peripheral face of the seal.

These two types may be distinguished as tangential chambers and enveloping chambers. The 70 cup-shaped, glass-walled treatment chamber 41d of Fig. 11 is shown in an exemplary application to a breast. It is provided with a pressure inlet fitting 42d, and associated pressure gage, connected with the treatment pressure hose 43. It 75

also has a thermometer 44d and electric heating element 45d. The sealing ring 48d is connected with the open end of the cup by a flexible collar which, by analogy, I shall call a cuff 46d which is held against the chamber by a clamping ring 41d. The skin-engaging surface 50d of the sealing ring 48d is on the lateral side rather than facing radially inwardly, but, as in the form of Fig. 6, it includes a central slot 52d defining concentric circular salient corners 53d and leading through a perforated skin-supporting wall 54d to the annular suction recess 51d.

Whereas in the encircling form of sealing ring the ring is preferably yieldable out of its round configuration, to accommodate itself to the contour of the limb, in the tangential application of Fig. 11 the sealing ring must be yieldable out of a plane, because there are few places on the body where a planar sealing ring would effect a close enough fit with the body area to provide a satisfactory seal. The flexibility of the rubber of which the sealing ring 48d is formed, permits it to be moved out of a plane to accommodate itself to the contour of the body. For holding the skin-engaging face 50d of the sealing ring in this non-planar body-conforming position I provide a plurality of, say, six arcuately spaced sockets 57 molded into the ring 48d. Each of the sockets 57 embraces the balled end of a threaded positioning rod 58. The rods 58 pass through ears 60 outstanding at corresponding arcuate intervals from the clamping ring 41d. By thumb nuts 59 engaging the upper and lower faces of each ear 60, each rod 58 may be positioned vertically to hold the sealing ring at that region at the desired height relative to the treatment chamber, to effect the conformation of the sealing ring to the body. The holes in the ears 60 through which the rods 58 pass, are preferably radially elongated because the radius of the rod from the vertical center line of the treatment chamber will vary at different elevations of the sealing ring.

In Fig. 11, it will be understood that the patient is lying on the back upon a treatment bed or table. For supporting the treatment chamber I provide a standard 62 which may rest upon the floor and carries a vertically adjustable U-shaped bracket 61, the arms of which are connected to diametrically opposite sides of the clamping ring 41d, as by trunnions.

The supporting standard not only relieves the patient of the weight of the treatment chamber, but, also, through the sealing ring positioning rods 58, definitely holds the sealing ring at a fixed elevation so that the skin is sucked up against the sealing ring rather than the sealing ring being sucked down against the skin and thereby constricting the circulation into the region being treated. The sealing ring so firmly engages the skin bounding the area being treated that, even though the treatment chamber be subjected to considerable negative pressure, the tendency of that treatment suction to pull the exposed area into the chamber is successfully resisted. The sealing ring 48d, while flexible, is sufficiently rigid to withstand such buckling as would ensnarl its perimeter, and thus the sealing ring itself can not be drawn radially inwardly or upwardly by negative pressure in the treatment chamber.

I shall next explain the apparatus for supplying controlled pressure to the treatment chamber and the sealing rings of the forms shown in Figs. 5 to 11, inclusive.

The specific type of treatment suction control apparatus which I have here shown somewhat

schematically in Figs. 12 to 17, inclusive, has been selected because it affords a wide range of flexibility. The treatment suction may be kept at a constant negative pressure or at a constant positive pressure, or it may be periodically varied between predetermined degrees of pressure, either all negative pressure or all positive pressure or alternating between positive and negative pressures, and the transitions between various degrees of pressure may be accomplished either abruptly or very gradually, and the time period of the cycle may be varied as well as the proportion of time allotted to each predetermined degree of pressure. In short, the pressure control is arranged to provide the desired degree of pressure in the treatment chamber for each moment throughout a predetermined cycle.

Such pressure control apparatus as here illustrated comprises (Fig. 12) an electric motor 65, a suction or negative pressure pump 66N, and a positive pressure pump 66P conveniently arranged upon a common base 68. Through a manually shiftable clutch 69 the motor drives a worm 70 which engages a worm wheel 71 on a transverse shaft 72. The worm wheel shaft 72 carries a lower stepped pulley 73 (Fig. 13) which drives an upper stepped pulley 74 on an upper pulley shaft 75, also journaled in a pulley frame 76, through a belt 77. The upper pulley shaft 75 also carries a cam wheel 78 which operates the pressure control valves as the cam wheel revolves. The cam wheel 78 has a peripheral rim 79 (Fig. 14) in the outer face of which is a centrally arranged annular slot 80 for the reception of the securing flanges of the various cam blocks B (Fig. 15).

A yoke-like bracket 81, which may be a fixed extension of the pulley frame 76, supports on one side of the cam wheel (Fig. 17) a positive pressure control valve indicated generally as 82P and on the other side a negative pressure control indicated generally as valve 82N.

I shall first describe in detail the positive pressure control valve 82P for the treatment chamber. A positive pressure control arm 83P is pivoted at one end at 84P on the fixed bracket 81, while the other end carries a roller 85P which engages the adjacent lateral cam faces of successive cam blocks B arranged about the periphery of the cam wheel rim 79. Through an adjustable cap screw 86P the arm 83P engages the inner spring cup 87P which embraces one end of a spiral regulating spring 88P, the other end of which is embraced by an outer spring cup 89P. The spring may be encased by a telescoping cylindrical shell 90P.

The outer spring cup 89P is mounted on the end of a protruding valve stem 91P which is slidably mounted in and extends through the valve body 92P. The valve stem carries a pair of spaced valve heads 93P cooperating with valve seats 94P to provide a substantially balanced valve. The valve controls the flow of air from the pump side passage 95P (which is connected by a pipe 96P to the discharge side of the positive pressure pump 66P) to the chamber side passage 97P of the valve body (which is connected through a pipe 98P to a T fitting 99 which, in turn, is connected to the hose 43 leading to the treatment chamber).

The valve stem 91P is normally urged to its closed position by a light biasing spring 100P. A diaphragm 101P is fixed across the open side of a cupped diaphragm housing 102P defining a diaphragm chamber 103P subject to the pres-

sure of the treatment chamber by a small tube 104P leading from the chamber 103P to the chamber side passage 97P.

The operation of the positive pressure control valve 82P, whose structure has just been described, is as follows: If the cam blocks B on the cam wheel have been so arranged as to call for positive pressure in the treatment chamber at some point in the revolution of the cam wheel (that is, at some period during the cycle of operation), the cam face of a suitably conformed cam block B will engage the roller 85P, camming it upwardly (Fig. 17) to swing it about the pivot 84P and thereby press the spring cup 81P upwardly. The diaphragm chamber 103P being at or under atmospheric pressure, no resistance is offered to the upward movement of the valve stem 91P, save the easily overcome biasing spring 100P. Accordingly, the valve heads 93P open, permitting air under positive pressure to pass from the pump side passage 95P (which is supplied in excess of maximum requirements by the positive pressure pump 66P) to the chamber side passage 97P and thence through the hose 43 to the treatment chamber. As pressure builds up in the treatment chamber it will correspondingly build up pressure in the diaphragm chamber 103P until the downward pressure on the diaphragm overbalances the pressure of the regulating spring 88P, corresponding to the compression as fixed by the position of the arm 83P, and upon the occurrence of such overbalancing the valve will be fully closed. Whenever the positive pressure in the suction chamber falls below that determined by the position of the arm 83P, the spring 88P will overbalance the reduced pressure in the diaphragm chamber 103P and reopen the valve until the pressure has again reached the predetermined degree.

When the cam blocks B call for a reduction in positive pressure, after a positive pressure has been built up, the arm 83P will swing downwardly leaving the valve closed. Ordinarily this would leave trapped in the treatment chamber 41 the maximum positive pressure which was built up and the treatment chamber positive pressure would not be reduced, as called for by the cams. To avoid such a situation I provide a relief vent valve 105 in the form of an adjustable needle valve which permits a small but constant bleeding of the chamber pressure line through the vent 106. This gives a fairly prompt relief for any positive pressure trapped in the treatment chamber after the cam wheel has required a lesser positive pressure. The relief needle valve 105 is set for such an adjustment that pressure will be relieved in the treatment chamber at the maximum rate at which it will be desired to have the pressure drop. On the other hand, the relief port will not be so great as to throw an unnecessary burden on the positive pressure pump or substantially impede the rapid building up of desired positive pressures within the treatment chamber.

When the treatment chamber is subject to negative pressure, the corresponding negative pressure will also obtain in the diaphragm chamber 103P, tending to lift the diaphragm 101P. It is therefore important that the upper end of the valve stem 91P merely abut the diaphragm 101P instead of being secured thereto, for otherwise, subjecting the treatment chamber to suction pressure would open the valve 82P and destroy the negative pressure.

I might explain, to avoid any confusion, that

in referring to Fig. 17, where I have used the terms "up" and "down" in connection with the operation of the valve parts, I am using the terms only in reference to the sheet; the figure is a horizontal plan section and the parts work in the horizontal plane.

The negative pressure control valve 82N, as will be seen from Fig. 17, is substantially similar in construction and operation to the positive pressure control valve 82P just described, save that the roller 85N contacts the opposite face of the several cam blocks B and the diaphragm chamber 103N is in reverse arrangement so that when it is subject to negative pressure the diaphragm 101N tends to close the valve.

The pump side passage 95N communicates with the pipe 96N leading to the intake of the negative pressure pump 66N.

The operation of the negative control valve is as follows: When the cam blocks B on the cam wheel engage the roller 85N to swing the control arm 83N downwardly tending to compress the spring 88N to open the valve, the diaphragm 101N yields, permitting the valve to open. Air is thus drawn from the treatment chamber 20 through the hose 43 and pipe 98N past the valve and through the pipe 96N to the suction pump 66N. When the negative pressure built up in the treatment chamber, and communicated to the diaphragm chamber 103N, is sufficient to overbalance the pressure of the spring 88N as compressed by the position of the arm 83N, the valve will close. The constant relief afforded by the valve 105 insures that when the cam wheel 25 calls for a decreased amount of negative suction 30 in the chamber, the high negative suction will not be permanently trapped in the treatment chamber.

Before describing in detail the arrangement of the cam blocks B on the cam wheel, I shall 40 explain the regulation of the sealing suction admitted to the sealing ring. The sealing suction regulating valve, indicated generally at 82S, is here shown as of substantially the same construction as the negative pressure regulating 45 valve 82N except that the regulating spring 88S is subjected to a predetermined pressure or setting by a suitably indexed hand screw 83S rather than by a cam-operated arm or lever. The pump side passage 95S of the valve communicates with 50 the negative pressure line 96N from the pump 66N while the sealing side passage 97S is connected to the sealing suction hose 55 leading to the sealing ring 48.

In the operation of the sealing ring it is often 55 desirable to employ a relatively high sealing suction initially to pull the skin into sealing contact with the ring and then drop the sealing suction to a lower suction merely sufficient to maintain the seal once it has been established. These predetermined sealing suctions may be secured by the manual adjusting screw 83S and aided by suitable indicia which may be placed on the hand wheel thereof. A pressure gage 107 subject to the sealing suction, is also provided.

After the high initial suction has effected the seal, and the sealing suction is to be reduced, to insure that the high suction will not be trapped in the sealing recess of the sealing ring 48, I provide an adjustable relief or bleeder valve 105S, 70 generally similar to the relief valve 105 for the treatment chamber. And similarly, this relief valve insures that the sealing suction is reduced to atmospheric pressure when the valve 82S is adjusted to cut off the sealing suction.

Referring again to the cam blocks B disposed in series about the periphery of the cam wheel 78, a typical cam block B is shown in Figs. 14 and 15. The top and bottom surfaces are arcuately conformed about a radius from the axis of the cam wheel 78 so that when the blocks are set on the cam wheel their undersides mate the peripheral face of the rim 79 of the cam wheel. Each block B carries a depending flange 110, which extends the length of the block at one lateral edge thereof. The flange 110 fits into the annular slot 80 on the peripheral face of the cam wheel 78 and is secured to the cam wheel by a locking pin 111 which extends through a hole 112 in the rim 79 and through a registering hole 113 in the flange 110. The locking pin 111 may have a protruding knurled head and a threaded portion which is screwed into the tapped end of the hole 112 for securing the locking pin. One face, 114, of each cam block B constitutes a cam face for engagement with one of the rollers 85P—85N. Each cam block, it will be seen, is reversible whereby it may be set into the slot 80 so that its cam face 114 will be presented to whichever of the rollers 85P—85N is required by the cycle to be established. The transverse distance between the cam face 114 and the securing flange 110 determines the lateral displacement of the roller by the cam block. The face 114 may be parallel with the flange 110, in which case the regulating valve will be held at a constant pressure during the arcuate travel of the block along the roller, or the face 114 may be at an inclination to the flange 110, in which case, when the given cam block passes the roller, the roller will be swung transversely outwardly or inwardly as the case may be.

For convenience in building up a series of cam blocks B to give the desired cammed contour to the cam wheel, the cam blocks, as to their arcuate lengths, are built up in multiples of 10 degrees. The peripheral face of the rim 79 may carry such radial indicia 115 as is shown in the development of the periphery of the cam wheel 45 which constitutes Fig. 16. When the blocks are worked out on the basis of 10-degree multiples, locking pin holes 112 occur every 10 degrees, thus making a total of 36 holes 112 about the lateral face of the cam wheel rim 79. It is only necessary, however, that a single locking pin be used for each cam block B although it is a convenience that the flange 110 of each cam block B be provided with a hole 112 for each 10 degrees of arcuate length of the cam block.

I contemplate that in a hospital or clinical installation of the treatment apparatus using the control here shown, a large variety of cam blocks B will be available. The several cam blocks will vary in arcuate length in the lateral displacement 60 of the cam face 114 from the securing flange 110 and in the inclination of the face 114 to the flange 110. Certain multiples for the transverse width of the cam block may be adhered to and indicated by indexed lines 116 engraved on the 65 peripheral face of the rim 29, as shown in Fig. 16. With the indicia 115 reading in terms of degrees and the transverse indicia 116 reading in terms of pressure, the peripheral face of the cam wheel rim 79 forms, in effect, the coordinated background or field for a pressure line which, instead of being drawn as a pencil line, is actually physically built up by the faces 114 of the cam blocks B.

In Fig. 16, going upwardly from the slot 80 represents positive pressure, while going downwardly from the slot 80 represents negative pres-

sure. In the exemplary instance of Fig. 16—where the cam profile has been built up to show the flexibility of the control rather than to show any therapeutically preferable cycle—the first cam block B1 has a cam face which is inclined 5 from initial zero position to a negative pressure position. The next cam B2 continues the inclination up to a predetermined level, which is sustained by the following three cam blocks B3, B4 and B5. As the cam wheel is revolved in the direction represented by the arrow in Fig. 16, the positive pressure roller 85P will ride against the back face of the cam blocks, retaining the positive pressure control valve 82P in its zero or closed position. The inclined cam faces of 10 the blocks B1 and B2, however, will gradually displace the roller 85N, causing corresponding negative pressure to be built up and maintained in the treatment chamber. After the negative pressure in the treatment chamber has been maintained at a constant amount during the passage 15 of the cam blocks B3, B4 and B5, the roller 85N next encounters another outwardly inclined cam block B6 which increases the negative suction in the treatment chamber and this higher negative pressure is maintained by the ensuing blocks 20 B7 and B8. In the instance of the latter two blocks, it will be seen that when a constant negative pressure is to be maintained for 50 degrees of revolution of the cam wheel, this may be effected by using one 20-degree cam block and one 30-degree cam block, both, of course, of width corresponding to the desired pressure to be maintained.

Still following the example of Fig. 16, the roller 35 85N would next be passed by the cam block B9 which is inclined slightly to reduce the degree of negative suction in the treatment chamber. It is at this point that the bleeder or relief valve 105 functions to avoid trapping in the treatment 40 chamber the high suction built up by the cams B6, B7, B8. Following the inclined cam B9, the slightly reduced negative pressure is maintained for another 40 degrees by the cam blocks B10 and B11. Then the inclined cam block B12 reduces the negative pressure to zero. It will be observed that by the great inclination of the cam face of the block B12, the negative pressure will be reduced to atmospheric pressure very rapidly 45 (in 10 degrees) as compared with the relatively 50 long period of build-up required through 60 degrees by the use of the gently tapered cam blocks B1 and B2.

The next cam block B13 provides zero pressure, 55 which means that the treatment chamber will be subject to atmospheric pressure. This is because, in the cam block B13, both lateral faces are within the zero pressure width, permitting both rollers 85P and 85N to stand in zero pressure position. The next cam B14 is arranged so that its inclined cam face is on the opposite side of the flange 110. The cam block B14 thus engages the positive pressure regulating roller 85P and gradually laterally displaces it to provide a constantly increasing positive pressure in the treatment chamber. This positive pressure is built up through 20 degrees and then maintained through 30 degrees by the cam block B15 and then returned through 20 degrees to zero pressure by the cam block B16. There is a short 10-degree 60 dwell at zero pressure or atmospheric pressure by the cam block B17. This completes the cycle 65 which will be immediately repeated by the continued rotation of the cam wheel. It will be observed that it is physically impossible, with cam 70 75

blocks of this design, to provide an anomalous situation supplying both negative and positive pressure simultaneously to the treatment chamber.

5 In this manner each revolution of the cam wheel 78 provides a cycle of operation for the treatment chamber, as regards the pressure therein. But the time period of that cycle is determined by the combination of pulleys employed 10 in the stepped pulleys 73 and 74, which can be so proportioned as to give any desired speed to the cam wheel. In instances where, for example, a predetermined suction pressure is to be maintained in the treatment chamber for a relatively 15 long period of time, the cam wheel may be rotated to a position corresponding to the desired negative pressure to be maintained, and the clutch 69 may then be disengaged, leaving the cam wheel stationary and maintaining the desired negative 20 suction in the treatment chamber until the clutch is again engaged.

It will be understood that the suction and pressure pumps 66N and 66P are of a blower type which inherently provide for their own relief 25 when they have built up their maximum suction or pressure. Where other types of pumps are employed it may be necessary to use, as a source of suction and pressure for the regulating valves, a pressure reservoir tank and a suction reservoir 30 tank suitably maintained by pressure controlled pumps.

While I have shown and described these specific embodiments of my invention, I contemplate that many changes may be made 35 therein without departing from the scope or spirit of my invention.

I claim:

1. A device of the character set forth comprising a chamber, a cover for said chamber provided 40 with an opening the size and shape of a human arm, a concave annular wall fitting into said opening, a section of foraminous material forming a part of said concave wall, an outer annular wall surrounding said inner wall forming a recess intermediate the walls, and means for reducing the 45 pressure within said recess.

2. The combination of a fluid pressure receptacle having an opening by means of which a part of a living body is exposed to the interior of 50 the receptacle, the mounting and arrangement of the receptacle relative to the body part being such that the receptacle is withheld from circulation-restricting movement against the body part by the pressure within the receptacle, a relatively rigid recessed member framing said opening, the recessed member having a pneumatically 55 permeable side communicating with the recess constructed and arranged for placement proximately facing the skin bounding the area of the body part exposed to the interior of the receptacle, and means for partially evacuating the recess to suck the skin into fluid-tight sealing contact with the permeable side and away from the adjacent portion of the body part, whereby 65 the recessed member is non-constrictive of vascular circulation.

3. The combination of a suction receptacle having an opening by means of which a part of a living body is exposed to the interior of the 70 receptacle, the mounting and arrangement of the receptacle relative to the body part being such that the receptacle is withheld from circulation-restricting movement against the body part, means for subjecting the interior of the 75 receptacle to varying abatmospheric fluid pressures,

a recessed member, of greater rigidity than the tissue of the body member, framing the opening and having a pneumatically permeable side communicating with the recess constructed and arranged for placement proximately facing the 5 skin bounding the body part area exposed to the interior of the receptacle, and means for partially evacuating the recess to such the skin into fluid-tight sealing contact with the permeable side and away from the adjacent portion of the body part 10 whereby the recessed member is non-constrictive of vascular circulation within the body part, the degree of suction in the recess being different from the degree of pressure in the receptacle.

4. A means for effecting a gas-tight seal between the wall of an opening into a receptacle and the skin of a portion of a living body tissue exposed by means of the opening to the interior of the receptacle, said means comprising a relatively rigid recessed member framing said opening, 20 said member having a side which may be brought into close proximity to the skin bounding the area exposed to the interior of the receptacle, the side comprising a pair of spaced apart annular salient surfaces for effecting primary seals with 25 the skin and a perforated skin-supporting member extending across the space between and offset from the salient surfaces, and means for partially evacuating the recess in said member to cause the proximate tissue to be sucked against the 30 open side thereof and away from the body tissue, whereby the recessed member is non-constrictive of vascular circulation within the body tissue.

5. The combination with a receptacle having an opening through which an extremity of a 35 living body extends into the interior of the receptacle for subjection to the pressure within the receptacle, and means for subjecting the interior of the receptacle to abatmospheric pressure,—of means for effecting a fluid-tight seal between the 40 receptacle and the body extremity said means comprising an annular sealing member, of greater rigidity than the tissues of the extremity, encircling the extremity and sealed to the receptacle and having a recess, a pneumatically permeable 45 wall for the sealing member communicating with the recess and arranged proximately to face the skin of the extremity, and means for subjecting the recess to suction to suck the skin, in a generally radial direction, away from the adjacent 50 portion of the body extremity, into, and to maintain it in, sealing contact with the sealing member.

6. The combination with a receptacle having an opening through which an extremity of a living body extends into the interior of the receptacle for subjection to the pressure within the receptacle, and means for subjecting the interior of the receptacle to varying abatmospheric pressures,—of means for effecting a fluid-tight seal 55 between the receptacle and the body extremity, said means comprising a relatively rigid annular sealing member encircling the extremity and sealed to the receptacle and having a pneumatically permeable side proximately facing the skin 60 of the extremity, a recess in the sealing member communicating with the permeable side and means for subjecting the recess to suction to suck the skin, more or less radially away from the body extremity, into, and to maintain it in, sealing 65 contact with the sealing member, the degree of suction in the recess being different from the degree of abatmospheric pressure presently within the receptacle.

7. The combination of a receptacle, means for 75

subjecting its interior to abatmospheric pressure, an opening in the receptacle through which a limb of a human body may pass for subjecting the limb to the interior pressure, a cuff sealed to the receptacle and encircling the limb at the margin of its exposure to the interior suction, and means for sucking the skin of the limb away from the limb and into sealing contact with the cuff, whereby the cuff is non-constrictive of vascular circulation within the leg.

8. A means for effecting a gas-tight seal between the wall of an opening into a primary treatment receptacle and a portion of living tissue exposed to the interior of the receptacle through the opening thereof, said means comprising a relatively rigid secondary recessed sealing chamber member framing the opening into the receptacle through which the tissue is exposed, said member having an open side which may be brought into close proximity to the tissue bounding the area exposed to the interior of the receptacle, and means for partially evacuating the recess in said member to cause the proximate tissue to be drawn out against the open side of the secondary recessed chamber member.

9. The method of treating a portion of a living body by fluid pressure which consists in exposing the portion to the interior of a treatment chamber by an opening thereinto, subjecting the chamber to abatmospheric treatment pressure, and pulling the proximate surface of said body portion into sealing contact with the margin of the opening by subjecting such surface to negative pressure different from the abatmospheric pressure in the treatment chamber.

10. The combination of a receptacle constituting a pneumatic treatment chamber subject to abatmospheric treatment pressure and having an opening for exposing a portion of a body member to the treatment chamber, a sealing ring around the opening sealed to the receptacle and comprising a lateral skin-engaging face, having a pair of spaced annular imperforate sealing margins, directed more or less flatwise against the annular area of skin bounding the portion exposed to the chamber through the opening, and passage means subjecting to suction portions of the skin-engaging face intermediate the spaced sealing margins for holding the skin in sealing engagement with the sealing ring.

11. The combination of a receptacle constituting a treatment chamber subject to abatmospheric pressure and having an opening for exposing a portion of a body member to the treatment chamber, a sealing ring having a skin-engaging face for application more or less flatwise to the body portion, a flexible sleeve sealing the ring to the receptacle, and a pneumatically permeable annular slot in the skin-engaging face of the sealing ring, and passage means for subjecting the slot to suction for holding the proximate skin in sealing contact with the sealing ring.

12. The combination of a receptacle constituting a treatment chamber subject to abatmospheric pressure and having an opening for exposing a portion of a body member to the treatment chamber, a sealing ring having a skin-engaging face for application more or less flatwise to the body portion, a flexible sleeve sealing the ring to the receptacle, and a pneumatically permeable annular slot in the skin-engaging face of the sealing ring, passage means for subjecting the slot to suction for holding the proximate skin in sealing contact with the sealing ring, and adjustable positioning means interposed between the receptacle

and the sealing ring for conforming the sealing ring to predetermined fixed non-planar contour whereby the skin-engaging face of the sealing ring may be conformed to the body surface.

13. The combination of a receptacle constituting a treatment chamber subject to abatmospheric pressure and having an opening for exposing a portion of a body member to the treatment chamber, a sealing ring having a skin-engaging face for application more or less flatwise to the body portion, a flexible sleeve sealing the ring to the receptacle, and a pneumatically permeable annular slot in the skin-engaging face of the sealing ring, passage means for subjecting the slot to suction for holding the proximate skin in sealing contact with the sealing ring, a fixed support, and adjustable positioning means for the sealing ring for conforming the sealing ring to predetermined fixed non-planar contour whereby the skin-engaging face of the sealing ring may be conformed to the body surface, the adjustable positioning means being interposed between the sealing ring and the support whereby the said proximate skin may be drawn away from the support upon which the body rests.

14. The combination of a receptacle constituting a treatment chamber subject to abatmospheric pressure and having an opening for exposing a portion of a body member to the treatment chamber, a sealing ring around the opening sealed to the receptacle and having a lateral skin-engaging face directed more or less flatwise against the annular area of skin bounding the portion exposed to the chamber through the opening, passage means subjecting the intermediate portion of the skin-engaging face to suction for holding the skin in sealing engagement with the sealing ring, and a support for the sealing ring independent of the body.

15. The method of sealing a pneumatic treatment chamber to the skin bounding a body portion exposed to the chamber which consists in supporting a sealing ring independently of the body in contoured position conforming to the body area and sucking the proximate skin into sealing contact with the ring by suction of a degree independent of the pressure in the treatment chamber.

16. A sealing ring of the class described formed of resilient rubber and having a skin-engaging annular face, a recess in the face, means for subjecting the recess to suction, and a perforated metal wall extending across the recess and annularly conformed and set back from the skin-engaging face to constitute a skin support between the edges of the recess, the edges of the metal wall being embedded in the rubber of the sealing ring.

17. A sealing ring of the class described comprising an annular skin-engaging face, an annular slot in the face defining spaced annular sealing edges, an annular recess back of the skin-engaging face, means for subjecting the recess to suction, an imperforate skin-supporting wall across the slot and extending annularly thereabout, and passage means laterally of the slot for the passage of air from the slot around the skin-supporting wall and into the suction recess.

18. Therapeutic apparatus comprising a receptacle having an opening through which a portion of the body of a patient may be exposed for subjection to abatmospheric fluid pressure treatment, a sealing ring framing the opening in the receptacle, said sealing ring having an open side to face the surface of the body of the patient,

means connected to the receptacle for periodically varying the atmospheric pressure to which the exposed portion of the patient's body is subjected, and means for applying a continuous suction to the sealing ring to cause the skin of the patient adjacent the margin of the opening in the receptacle to adhere over the open side of the sealing ring and thereby seal the receptacle to the patient.

10 19. Therapeutic apparatus comprising a receptacle having an opening through which a portion of the body of a patient may be exposed for subjection to fluid pressure treatment, a sealing ring framing the opening in the receptacle,

said sealing ring having an open side to face the surface of the body of the patient about the opening in the receptacle, means for periodically and alternately applying positive pressure and suction to the receptacle to subject thereto the exposed portion of the patient's body, and means for applying a sustained suction to the sealing ring to cause the skin of the patient adjacent the margin of the opening in the receptacle to adhere over the open side of the sealing ring 10 regardless of the variations of pressure conditions within the receptacle.

SIMON BENSON.
